METHOD AND APPARATUS FOR VALVING
INFLAMMABLE FLUIDSIsaac L. Rice, New York, N. Y., assignor to
Beatrice W. Rice, New York, N. Y.

Application March 7, 1938, Serial No. 194,389

9 Claims. (Cl. 244—135)

This invention relates to a method and apparatus for valving inflammable fluids.

Recent aircraft disasters, apparently brought about by the exploding and burning of fluids dumped or valved from the aircraft, have presented the problem of accomplishing this valving or dumping in a manner which would prevent such possible conflagration. In the case of heavier than air machines it often becomes necessary upon a moment's notice to dump the liquid fuel. With lighter than air machines it is customary to valve the lifting gas, as for example, hydrogen, when the craft is in the process of mooring.

The present invention has for its object the providing of a method and apparatus for valving inflammable gases or discharging inflammable fuels in such a manner that they are completely protected from sparks until they have reached a safe distance from the storage tank being valved.

Briefly, this is accomplished by discharging a fluid incapable of supporting combustion along with the inflammable fluid in such a manner that the first named fluid will temporarily envelop and surround the inflammable fluid until it is carried a safe distance from the aircraft.

Other objects and features of the invention have to do with details of construction of an apparatus for accomplishing the method of valving.

In the drawing:

Fig. 1 shows an airplane with a discharge spout designed in accordance with the present invention.

Fig. 2 illustrates a dirigible provided with a valving spout for the inflammable lifting gas and a discharge spout for the motor fuel.

Fig. 3 is a cross section of an airplane wing showing diagrammatically an arrangement for carrying out the present invention.

Fig. 4 is a detail view of a valving apparatus.

In accordance with the invention, the vehicle which is being provided with the safety discharge apparatus is provided with a supplementary storage tank in which may be held a non-inflammable fluid. The nature of this fluid may vary though it must in all cases be such that it will not support combustion. Carbon dioxide may be used since a small percentage of this gas will destroy the power of air to support combustion. A commercial product called Freon is desirable since it may be confined at lower pressures than CO_2 and yet it has a reasonably high specific volume. Consequently, lighter tanks could be used for its storage. Liquids such as water or carbon tetrachloride may also be utilized to form

a non-inflammable curtain around the fluid being valved from the aircraft or other moving or stationary object. The terms "non-inflammable" or "non-combustible" as applied to fluids in the following description and claims, are intended to refer to fluids incapable of uniting with oxygen to support combustion.

The outlet of the supplementary storage tank containing this non-combustible fluid is arranged preferably to surround the normal outlet of the liquid or gas to be valved. In the case of a liquid fuel being dumped, a discharge pipe 5 is preferably arranged as shown in Figs. 1, 2 and 3, so that the end extends substantially horizontally into the slip-stream of the aircraft. In case of a lighter than air fluid being valved, a discharge pipe 6 (Fig. 2) should be located on the upper side of the craft with the end pointing into the slip-stream. It is best that the non-inflammable fluid start to discharge shortly before the exit of the inflammable fluid and continue to discharge for a time after the inflammable fluid has ceased to flow.

In Figs. 3 and 4 is illustrated a partially diagrammatic arrangement adapted to carry out the invention with relation to an airplane in which a fuel tank 7 is carried in the wing. A supplementary storage tank is shown at 8. A valve 9 is connected to the latter tank by a pipe 10 and to the tank 7 by a pipe 11.

The valve 9 consists of a housing 12 having a cylindrical central recess and provided with a circumferential slot 13. Pipes 10 and 11 enter the housing 12 at ports 14 and 15, respectively. Within the central recess of housing 12 are nested cylindrical valve members 16 and 17, and extending radially from the latter is a discharge pipe composed of a fuel pipe 18 axially located within a supplementary fluid pipe 19. These pipes extend through the slot 13 and are rigidly affixed to the member 17 which is arranged to rotate within the housing 12. The central passageway of the pipe 18 is open to a port 20 in member 17 through a circumferential port 21 in member 16. The central passageway in pipe 19 which surrounds pipe 18 opens to a port 22 in member 17 through a passageway 23. The valve is operated by means of a lever 24 (Fig. 3) which is connected to members 16 and 17. This lever 24 is in turn operated by a cable 25 and lever 26 which is actuated from the control room of the plane.

In the operation: Assuming that tank 8 is carrying CO_2 at suitable pressure, when the airplane pilot desires to dump gasoline from tank 7, he

will move the valve 9 to such a position that port 22 in member 17 will coincide with port 14 in housing 12. Carbon dioxide gas will then flow in the passageway between pipe 19 and pipe 18. Upon further movement of valve 9 the port 20 will register with port 15 to permit fuel to flow through pipe 18 to the slip-stream of the plane.

Gasoline will thus be discharged within a wall of non-combustible gas which will be discharged with sufficient velocity to maintain the wall until the gasoline has been carried a safe distance from the ship.

In cutting off the valve 9 it will be seen that the port 15 will be cut off first and the carbon dioxide will flow for a certain time before it is shut off thereby insuring complete safety in the fuel discharge. If desired, a timing device may be arranged on the operating mechanism of valve 9 to positively provide for the initial and final flow of the non-inflammable gas before and after the flow of the fuel.

It is clear that the above described valving arrangement can be equally well adapted to the valve of a lighter than air gas, such as hydrogen. In this case, the valve will be arranged at the top of the ship as shown at 6 in Fig. 2.

The present invention is not limited to valving combustible fluids from aircraft but may also be used on stationary machines or land vehicles which must on occasion discharge inflammable fluid. For example, in purging a refrigerating machine of the inflammable gas, methyl chloride, it might be desirable to use my method and an apparatus similar to one I have disclosed.

What I claim is:

1. A method of valving inflammable fluid from aircraft which comprises initiating the flow of a stream of fluid incapable of supporting combustion in a direction away from said aircraft, discharging inflammable fluid in the same direction as said first fluid and positioning the stream of inflammable fluid in relation to said first stream of fluid to avoid combustion with the surrounding atmosphere.

2. A method of valving inflammable fluid from aircraft which comprises discharging from a conduit a fluid incapable of supporting combustion, and discharging said inflammable fluid from a conduit within the stream of said non-combustible fluid and in the same direction.

3. In an apparatus for valving inflammable fluid from a storage tank, a tank for non-inflammable fluid, a conduit means having an opening for discharging a stream of non-inflammable fluid from said last named tank, and a conduit means leading from said storage tank to the discharge opening of said first named conduit whereby said inflammable fluid is discharged within a stream of non-inflammable fluid, and valve means for opening said conduits so arranged that opening of said inflammable fluid conduit can take place only after said other conduit is open.

4. In an apparatus for valving inflammable fluid from a storage tank, a tank for non-inflammable fluid, a conduit means having an opening for discharging a stream of non-inflammable fluid from said last named tank, and a conduit means leading from said storage tank to the discharge opening of said first named conduit whereby said inflammable fluid is discharged within a stream of non-inflammable fluid, and valve means operable to open and close said non-inflammable fluid conduit respectively before and

after the open and close of said inflammable fluid conduit.

5. In an apparatus for rapidly valving inflammable fluids from the storage tank of an aircraft, a tank for containing a non-inflammable fluid, conduits leading from said tanks, a valve having entrance ports connected with said conduits, and a discharge pipe operably connected with said valve comprising an inner pipe adapted to be connected through said valve to the inflammable fluid storage tank and an outer pipe adapted to be connected through said valve to said non-inflammable fluid tank, the exit openings of said pipes being substantially coaxial whereby said inflammable and non-inflammable fluids may be freely discharged simultaneously from the pipes in the same direction.

6. In an apparatus for valving inflammable fluids from the storage tank of an aircraft, a tank for containing a non-inflammable fluid, conduits leading from said tanks, a valve housing having entrance ports connected with said conduits, a discharge pipe comprising an inner pipe and a substantially concentric outer pipe, and a movable valve member in said valve housing adapted upon movement in one direction to connect consecutively said outer pipe to said non-inflammable fluid conduit and said inner pipe to said inflammable fluid conduit.

7. An emergency device for emptying a fuel tank of an aircraft and preventing ignition of said fuel during said emptying, said device comprising: fuel discharge means for discharging a stream of said fuel from the exterior of said aircraft; and fluid discharge means for simultaneously discharging sufficient non-inflammable fluid from said aircraft in association with said stream of fuel during substantially the entire period of fuel discharge to prevent ignition of said fuel; said fuel discharge means including walls forming a passage for said stream of fuel from said tank and having a discharge port at the exterior of said aircraft; said fluid discharge means including a container for non-inflammable fluid carried by said aircraft, walls forming a conduit from said container and having a discharge port adjacent said stream of fuel; and control means for controlling the flow of fuel from said tank into said passage and providing for initiating discharge of said non-inflammable fluid from said aircraft substantially concurrently with the discharge of said fuel from said aircraft.

8. An emergency device for emptying a fuel tank of an aircraft and preventing ignition of said fuel during said emptying, said device comprising: fuel discharge means for discharging a stream of said fuel from the exterior of said aircraft; and fluid discharge means for simultaneously discharging sufficient non-inflammable fluid from said aircraft in association with said stream of fuel during substantially the entire period of fuel discharge to prevent ignition of said fuel; said fuel discharge means including walls forming a passage for said stream of fuel from said tank and having a discharge port at the exterior of said aircraft; said fluid discharge means including a container for non-inflammable fluid carried by said aircraft, walls forming a conduit from said container and having a discharge port substantially completely surrounding said discharge port for said passage, and control means for controlling the flow of fuel from said tank into said passage and providing for initiating discharge of said non-inflammable fluid from

said aircraft substantially concurrently with the discharge of said fuel from said aircraft.

9. An emergency device for emptying a fuel tank of an aircraft and preventing ignition of said fuel during said emptying, said device comprising: fuel discharge means for discharging a stream of said fuel from the exterior of said aircraft; and fluid discharge means for simultaneously discharging sufficient non-inflammable fluid from said aircraft in association with said stream of fuel during substantially the entire period of fuel discharge to prevent ignition of said fuel; said fuel discharge means including walls forming a passage for said stream of fuel

from said tank and having a discharge port at the exterior of said aircraft; said fluid discharge means including a container for non-inflammable fluid carried by said aircraft, walls forming a conduit from said container and having a discharge port communicating with said passageway through the walls thereof, and control means for controlling the flow of fuel from said tank into said passage and providing for initiating discharge of said non-inflammable fluid from said aircraft substantially concurrently with the discharge of said fuel from said aircraft.
